UNITED STATES PATENT OFFICE

98,971

DESIGN FOR A NURSING BOTTLE STERILIZER

Herbert B. Tyler, Berwyn, Ill., assignor of one-half to Charles A. Pipenhagen, Chicago, Ill.

Application January 13, 1936, Serial No. 60,543

Term of patent 14 years

To all whom it may concern:

Be it known that I, Herbert B. Tyler, a citizen of the United States, residing at Berwyn, in the county of Cook and State of Illinois, have invented a new, original, and ornamental Design for a Nursing Bottle Sterilizer, of which the following is a specification, reference being had to the accompanying drawing, forming part thereof.

Fig. 1 is a top plan view of a nursing bottle sterilizer embodying my new design;

Fig. 2 is a top plan section taken in the plane of the line 2—2 of Fig. 3 and looking in the direction indicated by the arrows; and

Fig. 3 is a side elevational view of the sterilizer.

I claim:

The ornamental design for a nursing bottle sterilizer, as shown.

In witness whereof, I hereunto subscribe my name, this 9 day of January, 1936.

HERBERT B. TYLER.
